SEWING MACHINE

Russell T. Edwards, Chicago, Ill., assignor to
Union Special Machine Company, Chicago, Ill.,
a corporation of Illinois

Application September 14, 1933, Serial No. 689,461

1 Claim. (Cl. 112—258)

The invention relates to new and useful improvements in sewing machines and more particularly to the means for mounting the sewing machine and the operating motor therefor.

5 An object of the invention is to provide a support to which the sewing machine and the operating motor may be rigidly attached, and to provide a resilient mounting for attachment of the support to the sewing machine table so that the sewing machine and the operating motor therefor may be maintained in a fixed predetermined relation to each other, and the vibrations incident to the operation of the parts of the motor and the sewing machine absorbed by

15 said resilient mounting.

A further object of the invention is to provide a supporting means of the above type for a sewing machine and its operating motor which is suspended beneath the sewing machine table with the sewing machine extending freely through an opening in the table and positioned for stitching material passing over the table while the motor is suspended beneath said supporting member, and is readily accessible for control by devices located beneath the table.

These and other objects will in part be obvious and will in part be hereinafter more fully disclosed.

In the drawings, which show by way of illustration one embodiment of the invention:

Figure 1 is a vertical sectional view through a sewing table showing a supporting means for the sewing machine and the driving motor embodying the invention.

35 Figure 2 is a similar view on the line 2—2 of Figure 1.

The invention is directed to a motor driven sewing machine and the mounting therefor. Both the sewing machine and the motor are rigidly attached to a common supporting member. The sewing machine is provided with the usual belt wheel, and said sewing machine is driven by a belt connection with a belt wheel associated with the motor. Inasmuch as the sewing machine and the motor are both mounted and rigidly attached to the common supporting member, the two belt wheels, one of which transmits motion to the other through the driving belt, will be held in a fixed predetermined relation to each other so that there will be no possible slippage of the belt on the belt wheels. The support on which the motor and the sewing machine are mounted is attached to the sewing machine table beneath the same; and through a resilient supporting means. Any vibrations imparted by the actuating parts of either the sewing machine or the motor to the supporting member therefor will be absorbed by the resilient mountings. The supporting member, as noted, is beneath the supporting table which is

provided with an opening of sufficient dimensions so that the sewing machine mounted on the supporting member beneath the table extends above the table and is thus positioned for the stitching of material passing over the sewing machine table. The motor is mounted on the underside of the supporting member and as shown includes an operating countershaft which has a clutch connection to the motor shaft, and the means for controlling this clutch connection is located beneath the sewing machine table where it may be readily accessible to the foot treadle or knee shift.

Referring more in detail to the drawings, a sewing machine table of the usual character is indicated at 1. This is preferably in the form of a table board. Said sewing machine table has an opening 2 therethrough. Located beneath the sewing machine table is a supporting member 3 in the form of a metal plate. The base portion 4 of the sewing machine is rigidly secured to this plate by clamping screws 5, 5. The sewing machine rests on the upper face of the plate 3 and the base portion 4 extends up through the opening 2 which is so dimensioned that the sewing machine is free from contact with the sewing table and rests solely on the plate 3. The sewing machine includes an overhanging arm 6 in which a needle bar carrying a needle 7 is mounted for reciprocation. Mounted on the base portion of the machine is a cloth plate 8 and the material is held on the cloth plate by the presser foot 9. Located within the base portion is a complementary stitching forming mechanism and a feed mechanism so that the material to be stitched is fed across the cloth plate beneath the presser foot 9. All of the actuating parts of the sewing machine are driven from an actuating shaft extending through the overhanging arm and on which is mounted a belt wheel 9a.

The supporting plate is considerably larger than the opening 2 and extends beyond the sides and ends thereof. This supporting plate 3 is suspended beneath the sewing machine table by hangers, each of which includes a resilient element. These hangers are all similar in construction and the description of one will answer for the others. Each hanger includes a bolt 10 which extends through the supporting plate 3. A nut 11 is threaded onto the bolt and then the bolt is inserted through an opening in the plate and a nut 12 is threaded onto the bolt beneath the plate. This makes a very rigid connection between the bolts and the plate 3. The bolt 10 extends upwardly through an opening 13 in the sewing machine table and is provided with a head 14 at its upper end. There is a recess 15 in the sewing machine table which is larger in diameter than the opening 13 and located in this recess is a resilient element which 60

includes a yielding cylinder 16 of rubber, cork, felt or the like having an opening centrally therethrough for the bolt 10. At the lower end of the cylinder is a metal cap 17 having an up-
5 standing flange adapted to engage the said cylinder. At the upper face of the said cylinder there is a cap 18 having a depending flange. This particular type of resilient element forms no part of the present invention per se, but is
10 shown and described in the application filed by Charles F. Rubel, May 19, 1932, Serial No. 612,372. The caps for the resilient cylinder are so dimensioned as to be out of rigid contact with the side walls of the recess, while the lower
15 cap 17 engages the bottom of the recess. This provides a resilient element wherein any lateral vibrations imparted to the bolt 10 will be cushioned and absorbed by the resilient cylinder. Likewise, vertical vibrations or movements im-
20 parted to the bolt 10 will be absorbed by these resilient cushioning cylinders.

As noted above, there are a series of these resilient elements supporting the plate 3 from the sewing machine table 1. The plate is ex-
25 tended laterally of the sewing machine, as shown in Fig. 1, and the driving motor for the sewing machine which is indicated at 19 is rigidly attached to this supporting plate 3 by clamping bolts 20, 20. The motor is an elec-
30 tric motor and in alignment with the shaft of the motor is a countershaft carrying a belt wheel 21. Between the shaft of the motor and this countershaft is a clutch controlled by a lever 23. The lever 23 is pivoted at 24 to the
35 frame of the motor and said lever at its free end is connected to a flexible member 25 which in turn may be connected to a foot treadle or knee shift.

A transmitting belt 26 runs over the belt
40 wheel 21 and over the belt wheel 9a. In the present embodiment of the invention, the shaft of the motor extends in a direction longitudinally of the sewing table 1, and the shaft of the sewing machine extends in a direction at
45 an angle approximating a right angle to the longitudinal axis of the sewing machine table. One strand of the transmitting belt, therefore, runs over an idler 27 carried by a bracket 28 which is fixed to the supporting plate 3. The
50 countershaft bearing the belt wheel 21 is mounted in the frame of the motor and is in effect a portion of the motor. Inasmuch as the belt wheel 21 is rigidly supported through the frame of the motor from the supporting plate 3, and also the belt wheel 9a is rigidly supported through the frame of the sewing machine by this supporting plate 3, these two belt wheels will always operate at a fixed and predetermined distance from each other. When the belt
55 is properly taut for transmitting motion from one belt wheel to the other, it will continue to do so without slippage due to vibrations disturbing this relation between the driving and driven belt wheels. Any vibrations incident to
60 the operation of the actuated parts in the sewing machine which are imparted to the supporting plate 3 will be absorbed by these cushioning elements which suspend the plate 3. Likewise any vibrations incident to the opera-
65 tion of the parts of the motor or the counter-
70 shaft carrying the belt wheel for operating the sewing machine will be absorbed by these resilient supporting members. Through this rigid

support for the sewing machine and the motor as a unit, and the resilient mounting of the support, vibrations incident to the operating of the parts are absorbed and at the same time these vibrations do not in any way disturb 5 the belt driving connection between the motor and the sewing machine.

While the sewing machine is mounted on the supporting plate suspended beneath the sewing machine table, it extends through an opening 10 in the table and is thus positioned so that the fabric passing over the table may be readily led across the cloth plate of the sewing machine beneath the presser foot for the stitching there-
15 of. As illustrated, the cloth plate is at a distance 15 above the upper surface of the sewing machine table and a cloth supporting tray 29 attached to the sewing machine table is so disposed relative to the cloth plate of the sewing machine that the fabric is freely directed onto and across 20 said cloth plate. The motor being mounted beneath the supporting plate carrying the sewing machine is positioned so that the control de-
25 vices therefor are readily accessible to a knee shift or treadle which necessarily is located be- 25 neath the sewing machine table.

While the sewing machine has been illustrated wherein the actuating shaft is approximately at a right angle to the longitudinal axis of the motor, it will be understood that the invention 30 may be used in connection with sewing machines of other types, the essential feature re-
siding in the rigid support of the sewing machine and the motor by the same supporting member so as to maintain a fixed predetermined posi- 35 tion between the driving shaft of the motor unit and the driven shaft of the sewing machine unit. While the motor as shown is used in connection with the countershaft and the control clutch which together constitute a driving elec- 40 tric transmitter, it will be understood from cer-
tain aspects of the invention that the belt wheel may be directly connected to the shaft of the motor and the motor controlled by the current passing therethrough. It is also obvious that 45 minor changes in the details of construction and the arrangement of parts may be made without departing from the spirit of the invention as set forth in the appended claim.

Having thus described the invention, what I 50 claim as new and desire to secure by Letters Patent, is:

The combination of a sewing machine having an actuating shaft, a belt wheel carried thereby, a driving motor for said sewing machine, a 55 belt wheel associated with said motor and operated thereby, a transmitting belt connecting said belt wheel of the motor with the belt wheel of the sewing machine, a supporting member disposed beneath said table and said opening and extending beyond the edges of the opening, a plurality of suspending bolts attached to said supporting member and extending through said table, resilient cushioning devices through which said bolts pass for supporting said member from 65 said table, means for rigidly mounting said sewing machine on said supporting member with the machine extending freely through said opening in the table, and means for rigidly mounting said motor on the underface of said support- 70 ing member.
